(57) **CLAIM**

I claim the ornamental design for a wine aerator, as shown.

DESCRIPTION

FIG. 1 is a perspective view of a wine aerator showing my new design;

FIG. 2 is a left side elevational view of the design shown in FIG. 1;

FIG. 3 is a front elevational view of the design as shown in FIG. 1;

FIG. 4 is the right side elevational view of the design as shown in FIG. 1;

FIG. 5 is the rear elevational view of the design as shown in FIG. 1;

FIG. 6 is the top plan view of the design as shown in FIG. 1; and,

FIG. 7 is the bottom plan view of the design as shown in FIG. 1.
